(57) **CLAIM**

The ornamental design for a grout float and grout float handle, as shown and described.

DESCRIPTION

This application discloses subject matter related to the subject matter disclosed in the following commonly owned, co-pending patent applications: (1) “Grout Float and Handle for Use with Same,” filed on Sep. 28, 2021 and assigned application Ser. No. 63/261,752, in the names of Clinton D. Bunch et al.; and (2) “Grout Float and Handle for Use with Same,” filed on Sep. 28, 2022 and assigned application Ser. No. 17/936,251, in the names of Clinton D. Bunch et al.; both of which are hereby incorporated by reference, in entirety, for all purposes.

FIG. 1 is a top left perspective view of a grout float and grout float handle;

FIG. 2 is a top right perspective view of a grout float and grout float handle shown in FIG. 1;

FIG. 3 is a bottom perspective view of the grout float and grout float handle shown in FIG. 1;

FIG. 4 is a top plan view of the grout float and grout float handle shown in FIG. 1;

FIG. 5 is a bottom plan view of the grout float and grout float handle shown in FIG. 1;

FIG. 6 is a left side elevation view of the grout float and grout float handle shown in FIG. 1;

FIG. 7 is a right side elevation view of the grout float and grout float handle shown in FIG. 1;

FIG. 8 is a rear elevation view of the grout float and grout float handle shown in FIG. 1; and,

FIG. 9 is a front elevation view of the grout float and grout float handle shown in FIG. 1.

1 Claim, 3 Drawing Sheets
